US00D775493S

(12) **United States Design Patent** (10) **Patent No.:** **US D775,493 S**
Funnell, II et al. (45) **Date of Patent:** **** Jan. 3, 2017**

(54) **CONTROL KNOB FOR A RANGE**(71) Applicant: **BSH Home Appliances Corporation**,
Irvine, CA (US)(72) Inventors: **Richard W. Funnell, II**, Corona del
Mar, CA (US); **Jonathan Grey**,
Huntersville, NC (US); **Graham
Sadler**, Huntington Beach, CA (US)(73) Assignee: **BSH Home Appliances Corporation**,
Irvine, CA (US)(**) Term: **14 Years**(21) Appl. No.: **29/525,050**(22) Filed: **Apr. 27, 2015****Related U.S. Application Data**(62) Division of application No. 29/468,887, filed on Oct.
4, 2013, now Pat. No. Des. 733,494, which is a
division of application No. 29/450,598, filed on Mar.
20, 2013, now Pat. No. Des. 697,755, which is a
division of application No. 29/425,868, filed on Jun.
28, 2012, now Pat. No. Des. 684,422, which is a
division of application No. 29/409,181, filed on Dec.
21, 2011, now Pat. No. Des. 668,105, which is a
division of application No. 29/389,416, filed on Apr.
12, 2011, now Pat. No. Des. 656,776.(51) **LOC (10) Cl.** ..... **07-02**(52) **U.S. Cl.**USPC ..... **D7/406**(58) **Field of Classification Search**USPC D7/340, 348, 350.1–350.4, 351, 402,
